SHOE WITH SOLE EDGE BINDING
AND WELT

William L. Mills, Keene, N. H., and Frederick W. Kruger, Worcester, Mass., assignors to Sealed Seam Welt Process, Inc., Boston, Mass., a corporation of Massachusetts

Application November 15, 1945, Serial No. 628,762

1 Claim. (Cl. 36—16)

1

This invention consists in a new and improved process of making welt shoes and in the novel shoe herein shown as produced thereby.

The general object of the invention is to produce a welt shoe of sturdy construction and attractive appearance while at the same time eliminating certain of the most troublesome and expensive operations heretofore considered necessary in the manufacture of welt shoes. For example, by the process of our invention channeling of the insole is avoided as well as the usual lip turning, setting and reinforcing operations on the insole, the upper trimming operation is dispensed with, and instead of the difficult inseam or a welt sewing step, we are able to secure the welt in place by employing a straight needle sewing machine.

In addition to the economies in manufacture above mentioned, we produce a shoe which is more flexible than welt shoes of conventional construction because we have no rib in the insole, we produce a welt seam which is completely sealed and so waterproof, we eliminate the objection of guttering and of the between substance breaking out between the stitches of the welt, and we reduce the overall thickness of the shoe bottom by eliminating any necessity for a layer of bottom filler. In addition we are able in most cases to eliminate the pulling-over, side lasting, inseam trimming and bed lasting operations.

These desirable results are secured by employing a composite binding and welt strip which may be attached to the insole by a vertical seam passing through its marginal edge, then wrapped or lasted about the margin of the insole in such a way as to locate the welt strip in a horizontal position projecting beyond the insole in convenient position to receive the outsole.

These and other features of the invention will be best understood and appreciated from the following description of a preferred manner of practising the process, illustrated in the accompanying drawings in which:

Fig. 1 is a view in perspective on a somewhat enlarged scale of the combined welt and binding strip employed in carrying out the process of our invention.

Fig. 2 is a cross sectional view on an enlarged scale illustrating the step of attaching the upper to the insole.

Fig. 3 is a similar view suggesting the additional step of attaching the combined binding and welt strip to the insole.

Fig. 4 is a similar view suggesting the steps of

lasting or wrapping the binding strip and attaching the outsole.

Fig. 5 is a fragmentary view illustrating a modification in the fitting of the upper and welt, and

Fig. 6 is a view in elevation of the forepart of the resulting shoe.

In practising the process of our invention we employ a combined binding and welt strip of the character shown in Fig. 1. This comprises a wide binding strip 10 which may be of leather or suitable textile material, and a slightly narrower welt strip 11 which may be of leather. These two strips are secured together by an intermediate stitchline 12 and a marginal stitchline 13. The two components of this combined strip are disposed with their grain or finished faces in contact, and the intermediate stitchline 12 is so located as to leave the upper or outer marginal edge of the welt 11 free.

20 The insole 14 may be of any desired thickness, for example, 3 to 9 irons. In carrying out our process it is practicable to use an insole as thin as 3 irons because the insole is not subjected to channeling. The marginal edge face 15 of the insole is preferably beveled at a slight inclination to the vertical, and its lower flat marginal face 16 is skived or beveled so that it is somewhat reduced in thickness as compared to the body of the insole. The upper 17 is cut accurately to pattern without lasting allowance and is now secured to the margin of the insole as suggested in Fig. 2 by a stitchline 18 which passes vertically through the margin of the insole and may be formed by a straight needle machine. In Fig. 2 the margin of the upper is shown as projecting downwardly somewhat over the marginal edge face of the insole, while in Fig. 5 it is shown as terminating substantially flush with that face. The construction shown in Fig. 5 is generally preferable since it permits the edge of the upper to be gauged flush with the margin of the insole.

25 The next step of the process consists in securing the margin of the combined binding and welt strip to the insole as suggested in Fig. 3; that is to say, by superposing its free margin above the upper and permanently securing it in this position by a vertical line of stitching 19 which is disposed slightly within the stitchline 18 securing the upper in place.

30 The next step of the process as herein illustrated consists in folding the combined strip 10—11 outwardly and downwardly, doubling the binding strip outwardly over its attached marginal portion, then wrapping it tightly about the margin of the insole, and finally drawing it, with

the attached welt strip 11, inwardly over the bottom face of the insole and cementing it securely in place. In this folding and wrapping operation the stitchlines 12 and 13 are brought beneath the insole, and the single-ply welt strip 11 is disposed in substantially horizontal position with its free edge projecting beyond the now bound edge of the insole. The welt is thus brought, without the necessity of any welt beating operation, into the horizontal position most convenient for reception of the outsole.

An outsole 20 is shown in Fig. 4 as secured to the welt strip 11 by a lock-stitch seam 21. It will be understood that the outsole is laid as in conventional shoemaking, and with the welt cemented in place the shoe may be presented to the rapid lock-stitch machine which is available for this operation. The binding strip with the attached welt is securely held in place by cement and this portion of the shoe bottom is further consolidated by the attachment of the outsole 20 which compresses the stitchlines 12 and 13 between itself and the bottom of the insole. The welt strip 11 projects outwardly beyond the contour of the binding strip so that it may be reached conveniently in the outsole stitching operation. The beveled bottom of the insole provides sufficient space for the reception of the inner portion of the combined binding and welt strip so that the outsole may directly engage the insole without the necessity of using bottom filler between the two soles. However, it would still be within the scope of our invention to dispense with the beveling of the insole if desired, and in that case a thin layer of bottom filler might prove desirable.

The shoe of our invention may be made by the slip-lasting or force-lasting process, that is to say, the last is forced into the upper only after the upper has been secured to the insole and at any convenient time before the outsole is layed. The binding strip may be turned either off the last or after the last has been inserted.

The shoe of our invention exhibits surprising flexibility for a welt shoe and this we believe is largely due to the fact that it contains no horizontally disposed seam, like the usual welt inseam, that tends to prevent bending of the shoe bottom. The usual welt seam is put under high tension when curved in the shoe bottom about the outer face of an insole, and there is no corresponding tension developed under the same circumstances by the vertical seams of our improved shoe.

As already noted, the several lines of fine stitching formed by straight needle sewing that secure the welt of our shoe in place obviate the danger of cutting or pulling through the welt always present in the conventional welt inseam and provide a particularly secure and convenient

welt-attaching means. Our construction also eliminates the chafing of the shoe parts and welt seam that frequently occurs in welt shoes.

While we have referred to a solid leather insole in the foregoing description, the choice of materials is not limited and anyone of the commercially available composition insoles, such as "Darex," may be used if desired. Moreover the combined binding and welt strip employed may, if desired, be molded as an integral strip from "Vinylite" or other suitable synthetic resin. In the illustrated embodiment of the invention the composite strip has the novel characteristic herein shown, viz., that the two portions are united in overlapping relation, with their inner edges substantially flush, and both have one free unattached margin.

The appearance of our improved shoe may be controlled by the thickness of the margin of the insole. If a thin insole, or one having a reduced margin, is employed the shoe will have a fine storm welt appearance, while a thick margin of insole will give a platform effect in the shoe. Moreover the heel seat may be stitched like the forepart or it may be lasted and tacked as preferred.

Having thus disclosed our invention and described in detail an illustrative embodiment thereof, we claim as new and desire to secure by Letters Patent:

A welt shoe having an unchanneled insole beveled about its outer marginal face, an upper with an out-turned margin stitched to the edge of the insole by a line of vertical stitching, a composite binding and welt strip stitched to the edge of the insole by a line of vertical stitching located inside the upper-attaching stitching and passing completely through the insole, said composite strip including a binding band wrapped about the edge of the insole and a single-ply welt strip stitched to the binding band and lying with its inner edge outside the inner edge of the binding band, and an outsole making flat contact with the insole and the welt strip and stitched thereto by a line of stitching located outside the outer contour of the binding band.

WILLIAM L. MILLS.
